PROCESS FOR PREPARING OXAMIDE

Jack Daniel Joffe, Hopewell, and Leland James Beckham, Bermuda District, Va., assignors to Allied Chemical & Dye Corporation, New York, N. Y., a corporation of New York

**No Drawing. Application February 21, 1950,
Serial No. 145,596**

13 Claims. (Cl. 260—561)

1

This invention relates to a process for preparing oxamide by the pyrolysis of ammonium oxalate, and more particularly to a process for carrying out the reaction in the presence of an acidic phosphorus-containing catalyst.

Oxamide is useful as a fertilizer. It has been prepared in the past by a number of processes including the pyrolysis of ammonium oxalate.

As carried out in the past, however, in the absence of a catalyst, the pyrolysis of ammonium oxalate resulted in only small yields of oxamide, for example of not more than about 28% of theoretical.

It is an object of this invention to provide a process for preparing oxamide by the pyrolysis of ammonium oxalate, in higher yields than have been obtained heretofore, and in a state of high purity.

This and other objects are accomplished according to our invention wherein ammonium oxalate is subjected to pyrolysis in the presence of an acidic phosphorus-containing catalyst.

In carrying out the process of our invention, ammonium oxalate (i. e. diammonium oxalate) and an acidic, phosphorus-containing catalyst are mixed and are heated in a suitable vessel to temperatures between about 155° C. and about 220° C. for the length of time desired, preferably for the length of time (at the temperature employed) required for obtaining the optimum yield of oxamide. During the course of the pyrolysis, the water of reaction may be condensed from the vapors formed in the pyrolysis and a periodic determination of the volume of water evolved serves as a measure of the rate at which the pyrolysis reaction is proceeding. The solid, substantially water-insoluble oxamide resulting from the pyrolysis remains in the pyrolysis vessel and is removed therefrom as such after substantial completion of the reaction, and may be separated from associated water-soluble impurities by washing with water to dissolve such impurities, and mechanically separating the solid, insoluble oxamide from the water solution containing the impurities.

The main reaction in the pyrolysis of ammonium oxalate to oxamide, proceeds as follows:

The desired reaction illustrated above is competitive with several other reactions, as is well known, which take place to some extent within the temperature range specified to produce as end products, ammonia, formic acid, CO_2 , CO , etc. We have found that by carrying out the pyrolysis of ammonium oxalate in the presence of an acidic, phosphorus-containing catalyst, and at temperatures within the range specified above, and preferably within the range between about 180° C . and about 200° C ., competing reactions are minimized relative to the desired reaction, and high yields of oxamide of high purity are obtained. At temperatures below about 180° C ., the illustrated reaction is inconveniently slow, while at temperatures above about 200° C ., certain of the competitive reactions, wherein CO_2 , CO and NH_3 are produced, are sharply increased, with an accompanying drop in the yield of oxamide.

The catalysts useful in our reaction are acidic, phosphorus-containing compounds, such as any of the phosphorus acids, their anhydrides and acid salts of alkali metals and ammonia and include the following:

P₂O₅—phosphorus pentoxide (phosphoric acid anhydride).

NaH₂PO₄—monosodium phosphate

NH₄H₂PO₄—monoammonium phosphate

$(\text{NH}_4)_2\text{HPO}_4$ —diammonium phosphate

The relative effects of these catalysts in comparison with a comparable run in which no catalyst was used are illustrated in Table I below.

Effect of catalysts on production of oxamide

Catalyst	Weight Percent Catalyst	Time of Reaction, Hours	Grams Sublimate (By- Product)	Oxamide Assay, Wt. Percent	Yield Oxamide, Percent Theor.
None		6	4.2	99.5	28.6
$\text{NH}_4\text{H}_2\text{PO}_4$	4	4	0.51	98.3	75.1
$(\text{NH}_4)_2\text{HPO}_4$	4	3.5	0.39	98.3	71.0
$\text{NaH}_2\text{PO}_4 \cdot \text{H}_2\text{O}$	5	4	0.55	98.0	71.4
P_2O_5	2.6	4.5	0.7	99.3	66.8

The ammonium oxalate and catalyst are preferably intimately mixed before subjecting the charge to pyrolysis. We have found that in general, a finely ground charge usually results in a higher yield of oxamide, other things being equal, and that best results are obtained when both the ammonium oxalate and the catalyst are finely divided. The catalyst is preferably of such fineness that all passes through a 100 mesh screen.

The effect of particle size of ammonium oxalate and catalyst on yield of oxamide is illustrated by the runs listed below in Table II.

TABLE II
Effect of particle size of ammonium oxalate and catalyst on yield of oxamide

Catalyst	Catalyst Mesh ¹	(COONH ₄) ₂ Mesh ¹	Time of Reaction, Hours	Yield Oxamide, Percent Theor.
NaH ₂ PO ₄ .H ₂ O	>100	>100	3.5	72.9
NaH ₂ PO ₄ .H ₂ O	>100	10-40	3.5	71.7
NaH ₂ PO ₄ .H ₂ O	30-40	10-40	5	64.0
NaH ₂ PO ₄ .H ₂ O	30-40	>100	5.5	58.4

¹ The values given show the screen size of particles in meshes per 1 linear inch.

The charge is preferably mixed dry, and for this purpose anhydrous ammonium oxalate may be used. However, the hydrated ammonium oxalate of commerce ((COONH₄)₂.H₂O) may be used, and the water removed during the pyrolysis. When P₂O₅ is used as the catalyst, however, we find it advantageous to mix the charge slightly wet to facilitate intimate mixing.

Any desired quantity of acidic, phosphorus-containing catalyst may be used to exert a promoting action upon the desired pyrolysis reaction illustrated. However, we prefer to use quantities equal to at least about 4% by weight of the charge to gain an appreciable promoting action, and generally quantities of not more than about 15% by weight of the charge are sufficient to give optimum yields consistent with practical operation. Usually a quantity of catalyst between about 5% and about 10% by weight of the charge is sufficient. The effect of varying catalyst quantity is illustrated by runs tabulated in Table III below.

TABLE III
Effect of catalyst quantity on rate of pyrolysis of ammonium oxalate to oxamide and on yield of oxamide.

Catalyst	Weight Percent Catalyst	Time of Reaction, Hours	Yield Oxamide, Percent Theor.
NH ₄ H ₂ PO ₄	25	5.5	85.4
NH ₄ H ₂ PO ₄	15	6.0	86.1
NH ₄ H ₂ PO ₄	10	6.5	84.3
NH ₄ H ₂ PO ₄	4	10	79.5

Our reaction is preferably carried out at normal atmospheric pressures or somewhat below. We find that pressures appreciably in excess of atmospheric (5170 mm. Hg) decrease the rate of reaction somewhat, while pressures below atmospheric down to about 200 mm. of mercury increase the rate of reaction slightly. Representative results are tabulated below in Table IV.

TABLE IV
Effect of pressure on the rate of pyrolysis of ammonium oxalate to oxamide

15	Catalyst	Weight Percent Catalyst	Time, Hours	Temp., °C.	Absolute Pressure, mm. Hg	Yield Oxamide, Percent Theor.
20	NaH ₂ PO ₄ .H ₂ O	5	17	200	5170	52.4
	NaH ₂ PO ₄ .H ₂ O	5	4	198	760	71.4
	NaH ₂ PO ₄ .H ₂ O	5	5.75	200	3-6	50
	NH ₄ H ₂ PO ₄	10	4.25	185	200	71.6
	NH ₄ H ₂ PO ₄	10	6.5	185	760	84.3

The rate of the reaction in the pyrolysis of ammonium oxalate to oxamide varies markedly with the temperature. We have found that the pyrolytic dehydration of ammonium oxalate to oxamide is a half order reaction which may be expressed according to the following equation

$$-\frac{d(AO)}{dt} = 2K\sqrt{AO}$$

where AO=ammonium oxalate concentration and that from the above equation, the reaction rates can be calculated by measurement of the volume of the water of pyrolysis. We have thus determined that the average optimum reaction time at 200° C. is about 4 hours, at 185° C. about 7 to 10 hours, while at 172°, a period of about 17 hours is required, as illustrated by the reactions listed in Table V below.

TABLE V
Effect of temperature on rate of pyrolysis of ammonium oxalate to oxamide

50	Temp., °C.	Catalyst	Weight Percent Catalyst	Time of Reaction, Hours	Yield Oxamide, Percent Theor.
200	NH ₄ H ₂ PO ₄	4		4	75.1
185	NH ₄ H ₂ PO ₄	4		10	79.5
172	NH ₄ H ₂ PO ₄	5		17	76.1

We have further found that an undue prolongation of time of reaction has a harmful effect on yield of oxamide as illustrated in Table VI below.

TABLE VI
Effect of increase of reaction time on yield of oxamide

55	Grams (COONH ₄) ₂	Catalyst	Weight Percent Catalyst	Temp., °C.	Time of Reaction, Hours	Yield Oxamide, Percent Theor.
25	NH ₄ H ₂ PO ₄	4		200	4	75.1
25	NH ₄ H ₂ PO ₄	4		200	10	71.0

5

Accordingly, we prefer to carry out the pyrolysis for periods not more than about 10 hours, and preferably for periods between about 2 and about 7 hours at the temperatures specified even though the reaction is not theoretically complete as measured by the amount of water of pyrolysis collected.

The following specific examples further illustrate our invention.

EXAMPLES 1-11

There are listed below in Table VII the conditions employed and the results obtained of working Examples 1-11 inclusive, run according to the general procedure set forth below, with the variations noted in the table, using a charge of anhydrous ammonium oxalate, together with a catalyst of the character contemplated by the invention. For comparative purposes, there are also listed at the end of the table, data covering a "control" run made under comparable conditions, but without a catalyst.

The runs of these examples were carried out by placing a charge of solid, anhydrous ammonium oxalate and catalyst in the quantities and fineness indicated, in a U-shaped pyrolysis tube, fitted with a thermocouple for recording inside temperature, and having one arm closed off with a stopper. Attached to the other arm of the U-tube was a sublimation tube consisting of an air-cooled condenser for condensing the water of pyrolysis. After charging ammonium oxalate and catalyst, the pyrolysis tube was placed in a heated oven, equipped with means for maintaining the temperature within 3° C. of the desired value. When the pyrolysis tube was in position in the oven, the sublimation tube connected thereto extended through an aperture in the oven, and was connected in turn to a graduated cylinder, surrounded by an ice bath, to collect and condense the water of pyrolysis. The apparatus was also provided with acid and base absorption vessels ("bubblers") for absorbing the NH₃ and CO₂ gases produced by the pyrolysis, and with a trap to prevent suck-back of acid or base into the graduated cylinder. After the charged tube was placed in the oven, it was brought to the desired reaction temperature, as indicated in the table, in a period of

6

about 15 minutes and the temperature was maintained at about this value for the period indicated.

The vaporous products of pyrolysis formed as the reaction proceeded—mainly water, NH₃, CO₂ and CO—were led through the sublimate tube where the water of pyrolysis condensed, then through the acid and base "bubblers" to absorb NH₃ and CO₂ respectively. The exit gas was mainly CO. The water condensed in the sublimate tube was led to the graduated cylinder where volume of water of pyrolysis was read and recorded at 30 minute intervals and served as a measure of the rate of reaction.

Tare weights of pyrolysis tube, sublimation tube and graduated cylinder were recorded before the reaction and weight differences were recorded at the completion of each run.

The solid residue, consisting mainly of oxamide, remaining in the pyrolysis tube was washed out of the tube with water, and the mixture was heated to 90° C. to dissolve the water-soluble impurities to facilitate their separation from the substantially water-insoluble oxamide. The mixture was then cooled to 30° C. to further decrease the solubility of the oxamide, then, filtered. To further purify the water-insoluble oxamide residue, it was again mixed with water, heated to 90° C., cooled to 30° C. and filtered. The recovered solid oxamide product was first air dried, then dried at 100° C. in an oven for several hours. The product was assayed for oxamide purity by hydrolyzing it with water and acid to oxalic acid, and titrating with KMnO₄. It will be observed that in the majority of the runs, an assay of 98% or more was obtained, although a few assay values below 95% were found. In these cases, elemental analyses of the samples were made and were found to be in agreement with the theoretical values for pure oxamide within the limits of experimental error. It is, therefore, apparent that our process yields a virtually pure oxamide product. It will be noted that yields of oxamide obtained in the runs of Examples 1-11 inclusive ranged from 50% to 80% of theoretical, whereas that obtained in the run in which no catalyst was used gave a yield of only 28%.

^a Time required to collect maximum amount of water.

^b Values exclude weight of catalyst used in each reaction.

^c For purposes of calculation, the solid sublimate was considered to be (NH₄)₂CO₃.H₂O.

^d Figures include solubility of oxamide (0.23 g. oxamide/500 ml. H₂O at 30° C.).

¹ Catalyst and oxalate mixed dry in Example 7.

² Several drops of H₂O added to catalyst and oxalate in Example 8.

³ Catalyst and oxalate mixed with 25 ml. H₂O in Example 9.

⁴ Reaction carried out at low pressure (2-15 mm. abs. range). Insoluble residue was considered 100% oxamide and sublimate titrated for oxamide.

⁵ The values given show the screen size of the particles in meshes per linear inch.

We claim:

1. In a process for preparing oxamide by the pyrolysis of ammonium oxalate, the step which comprises heating solid ammonium oxalate in the presence of a catalytic quantity of an inorganic acidic phosphorus-containing compound selected from the group consisting of phosphorus acids, anhydrides of phosphorus acids and alkali metal and ammonium acid salts of phosphorus acids at a temperature between about 155° C. and about 220° C.

2. In a process for preparing oxamide by the pyrolysis of ammonium oxalate, the step which comprises heating solid ammonium oxalate in the presence of a catalytic quantity of an inorganic acidic phosphorus-containing compound selected from the group consisting of phosphorus acids, anhydrides of phosphorus acids and alkali metal and ammonium acid salts of phosphorus acids at a temperature between about 180° C. and about 200° C.

3. In a process for preparing oxamide by the pyrolysis of ammonium oxalate, the steps which comprise mixing solid ammonium oxalate with a catalytic quantity of an inorganic acidic phosphorus-containing compound selected from the group consisting of phosphorus acids, anhydrides of phosphorus acids and alkali metal and ammonium acid salts of phosphorus acids and heating the resulting mixture at a temperature be-

tween about 180° C. and about 200° C. for a period between about 2 hours and about 7 hours.

5. In a process for preparing oxamide by the pyrolysis of ammonium oxalate, the steps which comprise mixing solid ammonium oxalate with a quantity of an inorganic acidic, phosphorus-containing compound catalyst selected from the group consisting of phosphorus acids, anhydrides of phosphorus acids and alkali metal and ammonium acid salts of phosphorus acids equal to between about 4% and about 15% by weight of the charge, and heating the resulting mixture at a temperature between about 180° C. and about 200° C., at a pressure between about 200 mm. of mercury and about 760 mm. of mercury for a period between about 2 and about 7 hours.

6. In a process for preparing oxamide by the pyrolysis of ammonium oxalate, the steps which comprise mixing solid ammonium oxalate with a quantity of monoammonium phosphate, equal to between about 4% and about 15% by weight of the charge and heating the resulting mixture, at a temperature between about 180° C. and about 200° C., at a pressure between about 200 mm. of mercury and about 760 mm. of mercury for a period between about 2 and about 7 hours.

7. In a process for preparing oxamide by the pyrolysis of ammonium oxalate, the steps which comprise mixing solid ammonium oxalate with a quantity of monosodium phosphate, equal to

between about 4% and about 15% by weight of the charge, and heating the resulting mixture at a temperature between about 180° C. and about 200° C., at a pressure between about 200 mm. of mercury and about 760 mm. of mercury for a period between about 2 and about 7 hours.

8. In a process for preparing oxamide by the pyrolysis of ammonium oxalate, the steps which comprise mixing solid ammonium oxalate with a quantity of diammonium phosphate, equal to between about 4% and about 15% by weight of the charge, and heating the resulting mixture at a temperature between about 180° C. and about 200° C., at a pressure between about 200 mm. of mercury and about 760 mm. of mercury for a period between about 2 and about 7 hours.

9. In a process for preparing oxamide by the pyrolysis of ammonium oxalate, the steps which comprise mixing solid ammonium oxalate with a quantity of phosphorus pentoxide, equal to between about 4% and about 15% by weight of the charge, and heating the resulting mixture at a temperature between about 180° C. and about 200° C., at a pressure between about 200 mm. of mercury and about 760 mm. of mercury for a period between about 2 and about 7 hours.

10. In a process for preparing oxamide by the pyrolysis of ammonium oxalate, the steps which comprise mixing solid ammonium oxalate with a quantity of phosphoric acid, equal to between about 4% and about 15% by weight of the charge, and heating the resulting mixture at a temperature between about 180° C. and about 200° C., at a pressure between about 200 mm. of mercury and about 760 mm. of mercury for a period between about 2 and about 7 hours.

11. In a process for preparing oxamide by the pyrolysis of ammonium oxalate, the step which comprises heating solid ammonium oxalate in the presence of a catalytic quantity of an inorganic acidic phosphorus compound selected from the group consisting of phosphorus acids, anhydrides

of phosphorus acids and alkali metal and ammonium acid salts of phosphorus acids, at a temperature between about 180° C. and about 200° C. for a period of not more than about 10 hours.

12. In a process for preparing oxamide by the pyrolysis of ammonium oxalate, the step which comprises heating solid ammonium oxalate in the presence of between about 4% and about 15% by weight based on the weight of the charge of an inorganic acidic phosphorus compound selected from the group consisting of phosphorus acids, anhydrides of phosphorus acids and alkali metal and ammonium acid salts of phosphorus acids, having a particle size such that all passes a 100 mesh screen, at a temperature between about 180° C. and about 200° C. for a period of not more than about 10 hours.

13. In a process for preparing oxamide by the pyrolysis of ammonium oxalate, the steps which comprise mixing solid ammonium oxalate with a catalytic quantity of an inorganic acidic phosphorus compound selected from the group consisting of phosphorus acids, anhydrides of phosphorus acids and alkali metal and ammonium acid salts of phosphorus acids, and heating the mixture at a temperature between about 180° C. and about 200° C. for a period of not more than about 10 hours.
